UNITED STATES PATENT OFFICE.

WILLIAM J. HEFFERNAN, OF ST. LOUIS, MISSOURI.

LOCOMOTIVE.

SPECIFICATION forming part of Letters Patent No. 355,608, dated January 4, 1887.

Application filed September 19, 1885. Serial No. 177,603. (No model.)

To all whom it may concern:

Be it known that I, WILLIAM J. HEFFERNAN, of St. Louis, Missouri, have made a new and useful Improvement in Locomotives, of which the following is a full, clear, and exact description, reference being had to the accompanying drawings, forming part of this specification, in which—

Figure 1 is a side elevation of my improved locomotive. Fig. 2 is a plan view of the same. Fig. 3 is a front elevation of the same, and Fig. 4 is a transverse section of one of the air-cylinders.

Like letters of reference indicate like parts wherever they occur.

In the drawings, A represents a locomotive having the usual boiler, A', and driving-cylinders C C.

Situate on and above the boiler B are the steam-cylinders D D, having pistons and piston-rods d d, which are connected with the crank-shaft E by connecting-bars d'. The shaft E is journaled on journals mounted on the boiler, and is connected by suitable cams, 25 yokes, and connecting-arms d² with the valve-rods d⁴, the valve-chambers d⁶ being situate on the cylinders D, and are connected with the steam-dome by pipes d⁸, provided with a throttle-valve, d⁷.

Keyed to the ends of the shaft E are wheels E', extending from which and pivoted thereto eccentrically are the connecting-rods e² e³, which are connected with sliding heads e', to which the piston-rods e of the air-compressing cylinders F F are connected. These cylinders F F are provided with suitable puppet-valves, f, (see Fig. 4,) for the admission of atmospheric air, and also discharge-pipes, also provided with similar puppet-valves, so that air may be

40 forced from the cylinders through the pipes G, by both strokes of the piston. These pipes G lead from the compressing-cylinders to the air-chamber H, which chamber is preferably situate in the frame of the locomotive below the boiler.

It will be noticed that there are several pipes G, each of which may be provided with shut-off valves G', so that any one of them may be shut off for repairs.

50 Instead of the air passing directly from the atmosphere to the cylinders F F, it is deliv-

ered by a blower or other device acting in the direction of the motion of the compressing-piston, so that the tendency to create a vacuum in the cylinder is neutralized. This is 55 shown in the drawings by the rotary blowers J, which are rotated by the belts K, passing over wheels on the shaft E, and the blowers are connected with the cylinders F by pipes j, which are provided with puppet-valves f, arranged to open and close with the movement of the pistons in the cylinders.

As already mentioned, the locomotive is provided with the usual driving-cylinders, C C, together with the customary valves and 65 other mechanism. The general motive power applied in these cylinders, however, is not derived from steam passing to the cylinders, but by the supply-pipe n, which leads from the air-chamber H, preferably following the course 70 of the usual steam-pipe, so that the general arrangement of mechanism may be followed to the valve-chambers C.

It is well known that in compressing air great heat is generated. To utilize this heat, 75 and to prevent it from causing injury, I form around the cylinders F F a water-jacket, l, and also around the air-chamber H, which jackets are connected by the pipes L L'. The pipe L' is connected with the water-tank by suitable 80 pipes and pump, the effect of which is to cause the water to flow through the jackets and pipes, and thereby not only keep the cylinders F and chamber H cool, but to heat the water which is supplied to the boiler.

In addition to the air-pipe leading from the chamber H to the cylinders C, the usual steam-pipe may be connected therewith, and a cut-off valve be provided, so as to cut off the air and turn on the steam.

90 I am aware that air-pumps operated by an auxiliary engine on locomotive-engines have been employed in connection with the driving-cylinders, and I do not desire to claim the same, broadly.

The advantages of my improvement are an increase in regularity of power and a saving of lost force through condensation.

Having thus described my invention, what I claim is—

1. In a locomotive, the combination of the auxiliary steam-engine, the air-compressor op-

erated by the engine, and an auxiliary blower for supplying air to the compressor, substantially as and for the purpose specified.

2. In a locomotive, the combination of an auxiliary steam-engine, a compressing air-pump operated by the steam-engine, a compressed-air chamber, an auxiliary blower operated by the steam-engine and connected with the air-compressor so as to supply air thereto,

and pipes connecting the air-chamber with the compressor and with the driving-cylinders of the locomotive, substantially as and for the purpose specified.

Witness my hand.

WILLIAM J. HEFFERNAN.
